UNITED STATES PATENT OFFICE.

PERLEY L. KIMBALL, OF BELLOW'S FALLS, VERMONT, ASSIGNOR TO VERMONT FARM MACHINE COMPANY, OF BELLOW'S FALLS, VERMONT, A CORPORATION OF VERMONT.

SUBDIVIDER FOR THE BOWLS OF CENTRIFUGAL LIQUID-SEPARATORS.

947,217.

Specification of Letters Patent. Patented Jan. 18, 1910.

Application filed January 19, 1909. Serial No. 473,045.

To all whom it may concern:

Be it known that I, PERLEY L. KIMBALL, a citizen of the United States of America, residing at Bellows Falls, in the county of 5 Windham and State of Vermont, have invented certain Improvements in Subdividers for the Bowls of Centrifugal Liquid-Separators.

This invention relates to improvements in 10 liquid subdividers for use in the bowl of a centrifugal liquid separator, and in the method of constructing such subdividers, and consists of a subdivider in which an annular perforated plate has the blades which 15 extend from the inner to the outer periphery of the annulus secured to such plate by means of lugs formed upon one edge of each blade and integral therewith, which lugs are passed through openings in the plate 20 and are turned over and clenched upon the side of the plate opposite to that from which the blade projects, and in the method of constructing such subdividers by forming openings for liquid in the annular plates, 25 arranged from the inner to the outer periphery of the annulus in lines corresponding to the desired line of the respective blades, forming integral lugs upon one edge of each blade, and securing them to the 30 plate by passing the lugs through the openings therein and bending the ends of the lugs over and clenching them upon the side of the plate opposite to that from which the blade projects; preferably also in forming 35 flanges at right angles to the plane of the blades and producing the lugs by cutting them from such flanges at intervals along their length, thereby leaving openings in the flanges which correspond to openings in the 40 plate.

In the accompanying drawings, Figure 1 is a plan view of a single plate with openings therein arranged in lines corresponding to a series of curved blades, three of which 45 are shown attached to the plate; Fig. 2 is an elevation of the parts shown in Fig. 1; Fig. 3 is a plan view of one of the blades with a flange from which fastening lugs have been cut; Figs. 4 and 5 are elevations of two, 50 blades in the positions in which they are to be attached to opposite sides of a perforated plate; Fig. 6 is a strengthening wire for the outer ends of a pair of contiguous opposite

blades; Fig. 7 is a vertical section of a portion of the plate shown in Fig. 1 on the line 55 of the outer margin of the flange of one of the blades; Figs. 8 and 9 show modifications in the construction and arrangement of lugs; Fig. 10 is a detail plan showing a blade attached to the plate by lugs extending from one edge of the blade; Fig. 11 is an elevation of a portion of two blades with lugs projecting from one edge of each and a section of a plate to which the blades are to be attached. 60

Designating the several parts of the device illustrated in the drawings by reference letters, A is the annular plate having a series of liquid openings *o* extending from the inner to the outer periphery of the annulus and arranged in rows corresponding to the desired line of the blades B, which in this case are curved and project at right angles to the plate A; but any other practical form may be used. 65

f are flanges upon the blades extending at right angles thereto, and having integral lugs *l'*, *l''* cut therefrom. The material cut from the flanges to form the lugs leave openings in the flanges which are located so as to correspond or register with openings *o* in the plate, when the blades are attached thereto. These lugs are advantageously cut and bent at right angles to the flange in such manner that when the blades 70 are to be attached in pairs, one upon each side of the plate and both in the same plane, a lug of a blade upon one side of the plate will pass through a hole at one limit thereof, and a lug of the blade on the opposite side 75 of the plate will pass through the same hole at the opposite limit thereof and the respective lugs will be bent over in opposite directions, as illustrated in Fig. 7; and when thus constructed and arranged it will be found 80 advantageous to have a portion of the lugs on each blade bent over in one direction and a portion in the other direction, as shown. 85

Modifications of the manner of forming the lugs of the respective blades and clenching them upon the plate are illustrated in Figs. 8 to 11, wherein in Fig. 8, the long 90 clenching lugs are all upon one blade, and the lugs *l''* upon the opposite blade are made only as long as the thickness of the plate and 95 simply hook upon the edge of the plate in 100

the opening, but do not extend through and clench over upon the opposite side of the plate; in Fig. 9, the lugs are in pairs, a short one l^3 , simply interlocks with the plate, and the other a long one, l^2 , passes through the plate and clenches upon the opposite side. In these modifications the short lugs serve to prevent any longitudinal movement of the blade along the surface of the plate, while the long lugs serve to secure the blades to the plate. In Figs. 10 and 11 are illustrated the manner of attaching the blades B to the plate A by means of lugs l^4 projecting directly from one edge of the blade instead of from flanges, as in the other figures. As shown in Fig. 10, the liquid openings o^2 in the plate A are formed with narrow elongations p in each direction, and a lug l^4 upon a blade on the opposite sides of the plate A, projects through one of these narrow elongations and each is bent over upon the plate in a direction opposite to that of the other, as illustrated. In Fig. 11 the blades upon opposite sides of the plate and with such lugs projecting from one of their edges, are shown in proper position for insertion through the narrow openings in the plate.

One advantage of having flanges upon the blades and cutting the lugs therefrom, is that the long lugs of each blade extend through the openings in the plate and in the flange of the opposite blade, and are clenched over and upon the flange of the opposite blade, thus serving as a means for securing both blades to the perforated plate by the lugs of either blade, and this is the preferable form. For the purpose of strengthening the ends of the blades at the outer periphery of the annular plate, that end is bent around a piece of stiff wire, and where the blades are secured to the plate in pairs, one upon each side of the plate and in the same plane, this stiffening wire extends across the width of the two blades, being made continuous from one to the other, and thus assists in holding the ends of the blades firmly upon the plate, particularly when the wire is soldered to the blades, as occurs in practice when each subdivider is dipped into melted tin after all the blades have been secured to the plate.

The flanged blades may be attached to the annular plates by other means than the integral lugs, for example, by rivets, but I have found the method of attachment by the integral lugs as hereinabove described to possess practical utilities superior to any other.

I claim:—

1. A subdivider for the bowl of a centrifugal liquid separator, consisting of an annular plate provided with a series of blades projecting at right angles thereto and secured to the plate by lugs extending from one edge of each blade through perforations in the plate, the ends of which lugs are bent

over and clenched upon the side of the plate opposite to that from which the blades project.

2. A subdivider for the bowl of a centrifugal liquid separator, consisting of a perforated annular plate provided with a series of blades projecting at right angles thereto upon each side thereof, and secured to the plate by lugs projecting from the contiguous edges of the blades, through the perforations in the plate, and the ends of such lugs being bent over and clenched upon the side of the plate opposite to that from which their respective blades project.

3. A subdivider for the bowl of a centrifugal liquid separator, consisting of an annular plate, a series of blades upon each side of the plate, each of which blades has a flange upon the edge next to the plate, the flange of each blade being provided with lugs which engage openings in the plate, and some of which extend through the openings and are bent over and upon the flange of the blade on the side of the plate opposite to that contiguous to the flange from which the lugs project, so as to secure to the plate a blade upon either side, by the lugs of the blade upon the opposite side.

4. A subdivider for the bowl of a centrifugal liquid separator, consisting of an annular plate and a series of curved blades having flanges upon one edge, which flanges are provided with lugs projecting therefrom through openings in the plate and the ends of such lugs being bent over and clenched upon the side of the plate opposite to that from which the blades project.

5. A subdivider for the bowl of a centrifugal liquid separator, consisting of an annular plate and a series of blades upon each side of the plate, which blades have flanges upon the edge next to the plate, the flange of each blade being provided with lugs, a plurality of which extend therefrom through openings in the plate and with the ends of such lugs bent over and upon the flange of a blade upon the side of the plate opposite to that of the flange from which the lugs project.

6. A subdivider for the bowl of a centrifugal liquid separator, consisting of an annular plate having openings arranged in lines extending from the inner to the outer periphery of the annulus, and a series of flanged blades projecting at right angles thereto, such flanges being provided with lugs integral with and formed from the flange by cutting openings therein corresponding to openings in the plate, a plurality of which lugs project through the said openings and have the ends thereof bent over and clenched upon the side of the plate opposite to that from which the blade projects.

7. A subdivider for the bowl of a cen-

- trifugal liquid separator, consisting of a perforated annular plate and a series of flanged blades projecting at right angles to the plane thereof, the flanges of the blade being provided with openings corresponding to openings in the plate, which flange openings are produced by cutting lugs therefrom, a portion upon one side of some of the openings and a portion upon the opposite side 10 of some other opening, said lugs passing through the plate openings and the ends of the lugs of the respective portions being bent over in opposite directions and clenched upon the plate.
- 15 8. A subdivider for the bowl of a centrifugal liquid separator, having an annular plate to which a series of blades are attached upon each side in pairs in the same plane at right angles to the plate, the outer ends of 20 each pair of blades being reinforced by a wire extending across the ends of the two blades and securely attached thereto.
9. A subdivider for the bowl of a centrifugal liquid separator, consisting of an annular plate having openings, for the passage 25 of liquid, arranged in lines extending from the inner to the outer periphery of the annulus, and a series of blades each provided with a flange upon one edge, which flanges 30 are secured to the annulus in such positions as to locate a blade between each two rows of openings in the annulus.
10. A subdivider for the bowl of a centrifugal liquid separator, consisting of an annular plate having openings, for the passage 35 of liquid, arranged in lines extending from the inner to the outer periphery of the annulus, and a series of blades each having a flange upon one edge projecting at right 40 angles to the blade and provided with openings corresponding to liquid openings in the annular plate, which flanges are secured to said plate so as to locate each blade between two lines of liquid openings.
- 45 11. The method of constructing subdividers, having an annular plate with blades projecting at right angles thereto, for the bowl of a centrifugal liquid separator, which consists in forming a series of openings in 50 the annular plate arranged in lines extending from the inner to the outer periphery of the annulus, corresponding to the desired line of the respective blades, forming integral lugs upon one edge of each blade and 55 securing them to the plates by passing the lugs through said openings and bending them over and clenching them upon the side of the plate opposite to that occupied by the blade from which such lug projects.
12. The method of constructing subdividers having an annular plate with blades projecting at right angles to the plane thereof, for the bowl of a centrifugal liquid separator, which consists in forming a series of openings for liquid in the annular plate, arranged in lines extending from the inner to the outer periphery of the annulus, corresponding to the desired line of the respective blades, forming flanges upon one edge of each blade and openings therein corresponding to openings in the plate; by cutting lugs from the flange to correspond to the location of a plurality of openings in the plate, passing such lugs through such openings in the plate and clenching their ends upon the side 65 of the plate opposite to that upon which the flanges bear.
13. The method of constructing subdividers having an annular plate with blades projecting at right angles to the plane thereof upon each side, for use in the bowl of a centrifugal liquid separator, which consists in forming a series of openings in the plate for the passage of liquid, which openings are arranged in lines extending from the inner to the outer periphery of the annulus corresponding to the desired line of the respective blades; forming flanges upon one edge of each blade and making openings in the flanges corresponding to openings in the 80 plate, by cutting lugs therefrom at locations to correspond with the location of a plurality of openings in the plate; passing a plurality of the lugs through openings in the plate and one of the flanges and clenching the ends of such lugs upon the flange through the openings of which they pass.
14. A subdivider for the bowl of a centrifugal liquid separator, consisting of an annular plate interposed between two series of spaced plates, which are arranged in pairs at right angles to the annulus in coincident planes upon opposite sides thereof, and securely connected therewith by interlocking portions of the plates of the series.
